[57] CLAIM

The ornamental design for a shower escutcheon, as shown and described.

DESCRIPTION

FIG. 1 is a perspective view of a shower escutcheon showing our new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a cross-sectional view taken along line 7—7 in FIG. 1; and,

FIG. 8 is a cross-sectional view taken along line 8—8 in FIG. 1.

The broken line showing of the handle in FIGS. 1—6 is for purposes of illustration only and forms no part of the claimed design.
